DESIGN FOR A SERVICE STATION

Alfred H. Jaehne, San Francisco, Calif., assignor,
by mesne assignments, to California Research
Corporation, San Francisco, Calif., a corpora-
tion of Delaware

Application March 25, 1946, Serial No. 127,929

Term of patent 14 years

(Cl. D13—1)

To all whom it may concern:

Be it known that I, Alfred H. Jaehne, citizen
of the United States of America, residing in the
city and county of San Francisco, State of Califor-
nia, have invented a new, original, and ornamental
Design for a Service Station, of which
the following is a specification, reference being
had to the accompanying drawing, forming part
thereof.

Figure 1 is a top plan view of a service station
showing my new design; Figure 2 is a front per-
spective view; and Figure 3 is a side perspective
view thereof.

I claim:

The ornamental design for a service station, as
shown.

ALFRED H. JAEHNE.
